UNITED STATES PATENT OFFICE.

VANE R. TIFT, OF PILGER, NEBRASKA.

BRICK-TONGS.

No. 800,841.

Specification of Letters Patent.

Patented Sept. 26, 1905.

Application filed January 21, 1905. Serial No. 242,072.

To all whom it may concern:

Be it known that I, VANE R. TIFT, a citizen of the United States, residing at Pilger, in the county of Stanton and State of Nebraska, have 5 invented a certain new and useful Brick-Tongs, of which the following is a specification.

The objects of my invention are to provide a device for lifting brick, which is adapted for lifting rows of bricks of different widths 10 and so constructed that a row of bricks will be firmly held between the jaws, because these jaws are forced toward each other as the handle is grasped for raising the tongs.

A further object is to provide means adapted 15 to be engaged by the handle of the tongs which are adapted to hold the jaws in position relative to each other. These means for holding the jaws in position relative together are so arranged that they can be released by 20 the handle being forced toward them, so that the adjustment of the jaws may be easily had.

My invention consists in certain details in the construction, arrangement, and combination of the various parts of the device where- 25 by the objects contemplated are attained, as hereinafter more fully set forth, pointed out in my claims, and illustrated in the accompa- nying drawings, in which—

Figure 1 is a side elevation of the device, 30 showing in section a part of it. Fig. 2 shows in perspective the device on a row of bricks in position for lifting; and Fig. 3 is a side elevation of the modified form of the tongs, showing in section the adjustable portion 35 thereof.

Referring to the accompanying drawings, I have used the reference-numeral 10 to indicate the tube, having the jaw 11 pivoted at one end thereof, said jaw having a handle 12 40 at the upper portion thereof and at substantially right angles to it.

The numeral 13 designates the pivot between the jaw 11 and the tube 10. In the upper portion of the tube I have cut away the 45 upper portion of that end of the tube 10 which is away from the pivot 13 to form a slot 14 therein.

On the upper portion of the sides of the tube 10, caused by making the slot 14, I have 50 provided the series of ratchets 15 and 16. I have also provided a collar 17 at the extreme end of the tube 10, which is away from the pivot 13. Slidably mounted in the tube 10 is the bar 18, having the jaw 19 fixed at its 55 outer end. Pivotsly mounted at the inner end of the bar 18 in such a way that it will

extend upwardly through the slot 14 is the pawl 20, which is designed to engage the ratchets 15 and 16 normally and to be held in engagement therewith by the spring 21, which 60 is mounted at the extreme inner end of the bar 18 and which is between said bar and the inner end of the pawl 20.

It will be seen by an examination of Fig. 1 that when the jaw 19 is at its extreme limit 65 of movement away from the jaw 11 the jaw 19 can be moved toward the jaw 11, as the pawl 20 will slide over the ratchets 15 and 16, and the jaw 19 will be held relative to the jaw 11 when it has been moved to the desired position. When the jaw 19 is at its inner limit 70 of movement and it is desired to move it outwardly and away from the jaw 11, the operator simply places his hand over the handle 12 and under the tube 10, and by grasping 75 these parts draws them together and forces the inner end of the pawl 20 downwardly against the resistance of the spring 21, which causes the outer end of the pawl 20 to be raised out of engagement with the ratchets 80 15 and 16, and thus enables the operator to pull the jaw 19 away from the jaw 11. Thus it will be seen that the movement of the jaw 19 away from the jaw 11 can be easily and readily accomplished.

In the modified form of the device shown in Fig. 3 there is a screw-threaded portion 22 at the outer end of the tube 10, into which a screw-threaded rod 23, which takes the place of the bar 18, is screwed and the adjustment 90 secured by screwing or unscrewing the screw-threaded rod 23.

In practical use it is very advantageous to have the jaws so arranged that they may be adjusted toward or away from each other, so 95 that if the bricks vary in width the adjustment may be made, or if it is desired to grasp more or less bricks this may be readily and easily accomplished.

Having thus described my invention, what 100 I claim, and desire to secure by Letters Patent of the United States therefor, is—

1. A tube having a slot in its upper portion, ratchets forming the edges of the slot, a jaw pivoted to the tube, a handle attached 105 to the jaw and extending over the tube to a position above the ratchets, a bar slidably mounted in the tube, a jaw attached to the outer end of said bar and means designed to engage the ratchets for securing the bar 110 against outward movement relative to the tube.

2. A tube having a slot in its upper portion, ratchets forming the edges of the slot, a jaw pivoted to the tube, a handle attached to the jaw and extending over the tube to a position above the ratchets, a bar slidingly mounted in the tube, a jaw attached to the outer end of said bar, and spring-actuated means designed to engage the ratchets for securing the bar against outward movement relative to the tube.
3. A tube having a slot in its upper portion, ratchets forming the edges of the slot, a jaw pivoted to the tube, a handle attached to the jaw and extending over the tube to a position above the ratchets, a bar slidingly mounted in the tube, a jaw attached to the outer end of said bar, a spring-actuated pawl pivoted to said bar for engaging the ratchets designed to be engaged by the handle for forcing the pawl out of engagement with the ratchets.
4. A brick-carrier comprising two jaws,

means attached to the jaws for holding them in position relative to each other, a handle attached to one of the jaws, means for securing the jaws in position relative to each other designed to be released by the handle. 25

5. In a brick-carrier comprising two jaws slidingly mounted relative to each other, a handle attached to one of the jaws, means for securing the jaws in position relative to each other, said means being so arranged that it can be released by the handle. 30

6. In a brick-carrier, a tube, a handle, a bearing-jaw pivoted to the tube, a jaw-carrying bar slidingly mounted in the tube, means attached to the bar for holding it against outward movement relative to the tube and permitting of inward movement relative thereto, said means to be released by the handle. 35 40
